UNITED STATES PATENT OFFICE.

FRANCIS B. PERKINS, OF BOSTON, MASSACHUSETTS.

ELECTRIC ELEVATOR.

SPECIFICATION forming part of Letters Patent No. 509,821, dated November 28, 1893.

Application filed March 16, 1889. Serial No. 303,565. (No model.)

To all whom it may concern:

Be it known that I, FRANCIS B. PERKINS, of Boston, county of Suffolk, State of Massachusetts, have invented an Improvement in Elevators, of which the following description, in connection with the accompanying drawings, is a specification, like letters on the drawings representing like parts.

This invention relates to hydraulic elevator systems wherein the fluid to actuate the elevator is stored in a tank, under pressure, by means of a pump operated by an electric motor.

Prior to this invention, it has been customary to stop the motor and pump, whenever the pressure in the pressure tank has reached a certain predetermined point, the motor and the pump being started when the pressure has been reduced by operation of the elevator, to restore the pressure to the required point.

In United States Patent, No. 399,716, dated March 19, 1891, a device is represented, for automatically starting and stopping the motor and pump as required; to maintain the proper pressure in the pressure tank; but it has been found in practice, has an injurious effect upon the line or circuit in which the motor is placed, and which usually contains one or more electric lights or other translating devices, the effect upon the line or circuit being particularly noticeable when incandescent lamps are included in the circuit.

This invention has for its object to provide an apparatus which shall overcome the objections referred to, and which may be employed or operated in connection with any circuit, containing any number of translating devices, without danger of injuring the effect of the latter.

In this invention, the motor which is a self-regulating one and pump are not stopped whenever the pressure in the pressure tank shall have reached the predetermined point; but are permitted to run continuously, thereby obviating the injurious effect caused by starting and stopping the motor at frequent intervals.

In accordance with this invention, suitable means are provided, controlled by the pressure in the pressure tank, whereby the delivery of the pump, to the pressure tank, may

be controlled in such a manner as to maintain the pressure at the required point without stopping the pump.

One part of this invention in hydraulic elevator systems, therefore, consists in the combination of the following instrumentalities, viz:—an electric circuit containing translating devices, a continuously running self-regulating motor, placed in circuit therewith, a pressure tank to contain fluid to actuate the elevator; a pump operated by said continuously running motor, and delivering into said pressure tank, and a valve actuated by pressure in the pressure tank to regulate the amount of delivery from the pump to the pressure tank, substantially as will be described.

Other features of this invention will be hereinafter described and pointed out in the claims at the end of this specification.

Figure 1 in elevation represents a sufficient portion of a building provided with a hydraulic elevator operated in accordance with my invention, to enable the latter to be understood, and Fig. 2 a detail to be referred to, it being a section on the line $x-x$ Fig. 1 looking toward the left, and Fig. 3, a diagram showing the motor included in the circuit containing translating devices.

The elevator car A suspended in the elevator well or shaft A' by the rope a passed about the sheave a', and having its other end passed about a fixed sheave a² and connected to a movable sheave a³, may be such as now commonly used on hydraulic elevators, especially of that class known as the "Hinckle" system. The movable sheave a³ is moved away from the fixed sheave a² by an engine a⁴, having its inlet pipe a⁵ connected to the bottom of a tank a⁶ and having its outlet pipe a⁷ connected to a second tank a⁸. The tank a⁶ will preferably be a closed tank having its inlet pipe b connected to a pump b', and forming the outlet pipe for the same, the inlet pipe b² for the said pump being connected to the tank a⁸ near its bottom.

The pump b' is driven, in accordance with my invention, by an electric motor c, which may be of any usual or well known self regulating type, having mounted upon its armature shaft the pulley c', connected by a belt c² to a preferably larger pulley c³ on a shaft

c^4 having bearings, as herein shown, in hang-
ers c^5 suspended from the ceiling c^6 . The shaft
 c^4 is provided with a second smaller pulley c^7
which is connected by a belt c^8 to a pulley c^9
5 on a shaft c^{10} , having mounted upon it a crank
disk c^{12} to which the connecting rod c^{13} of the
pump is joined.

The electric motor c , herein represented as
a shunt wound motor, see Fig. 3, derives its
10 current of electricity by means of wires d ,
from the main line or circuit d' , the latter
containing, as represented in the drawings,
one or more translating devices herein repre-
sented as incandescent electric lamps c^{10} .

15 While I prefer to employ a shunt wound
motor, as shown, for the reason that such a
motor presents the simplest form of self regu-
lating motor, that is, a motor which will main-
tain a substantially constant speed irrespect-
20 ive of the load thrown upon it, still I desire
it to be understood, that any other self regu-
lating motor may be employed, or any other
self regulating device applied to a motor
whereby the latter is caused to maintain a
25 constant speed irrespective of the load.

The rotation of the armature shaft of the
electric motor through the system of belts re-
ferred to, drives the pump and forces the
water through the inlet pipe b into the tank
30 a^6 , where it is stored under pressure to be used
for raising the elevator.

In practice it is desired that the pressure
in the tank a^6 should not exceed a predeter-
mined or desired amount, as for instance, sev-
35 enty pounds, and in order that the pressure
may not exceed the desired amount, I have
provided a regulator herein shown as the
well known "Clark" diaphragm regulator by
which the supply of water to the tank a^6 is
40 automatically cut off when the pressure has
reached the desired amount. The regulator
consists of a diaphragm located between an
upper chamber d and a lower chamber d' , the
lower chamber being connected by a pipe d^2
45 with the tank a^6 . The upper chamber d is
provided with an opening through which is
extended a pin or stem d^4 on a lever b^7 piv-
oted, as herein shown at d^5 to the pressure
tank, and having its other end connected by
50 link b^6 , see Fig. 2, to a rod b^5 fastened to the
valve stem b^4 of a valve located in a pipe b^3
connected to the inlet pipe b . The inlet pipe
 b between the branch pipe b^3 and the pres-
sure tank is provided, as herein shown, pref-
55 erably with a check valve d^6 of any usual or
well known construction.

In operation the electric motor is run con-
tinuously by a current fed from the main
wires, and continuously drives the pump b' ,
60 thus forcing water into the tank a^6 until the
desired pressure has been attained in the
said tank. When the pressure in the tank
has reached a predetermined amount, the
diaphragm of the regulator is raised by the
65 said pressure and the lever b^7 lifted, thus
turning the valve stem b^4 through the link b^6
and rod b^5 and opening the valve in the branch

70 pipe b^3 , permitting the water forced by the
pump to flow through the said branch pipe.
As the valve in the branch pipe is opened
the pressure upon the front side of the check
valve d^6 is reduced and the said check valve
is closed by the back pressure from the tank
 a^6 . As herein shown, the branch pipe b^3 dis-
charges into the waste-water tank a^8 , from
75 which it is again drawn by the pump b' . It
will thus be seen that a continuous circula-
tion of water through the pump and waste
tank a^8 is maintained, when the pressure in
the pressure tank a^6 has reached a normal or
80 desired amount.

The amount of pressure in the tank a^6 may
be varied, as shown, by a weight or ball e ad-
justable on the lever b^7 . As soon as the
pressure in the tank a^6 has been reduced, as
85 by the starting of the elevator, the pressure
upon the diaphragm of the regulator is re-
duced in the same proportion, and the valve
in the branch pipe b^3 is closed, so that the
water withdrawn from the waste tank a^8 is
90 again pumped into the pressure tank a^6 to
once more restore the pressure therein to the
normal or desired amount.

I prefer to employ the check valve, but the
same might be dispensed with and the valve
95 in the branch pipe be so constructed, as for
instance it might be made smaller, so that
when opened by the regulator, a sufficient
amount of water will be discharged through
the said valve to keep the pressure in the
100 tank a^6 substantially constant, after the pres-
sure in the said tank has reached a predeter-
mined or certain point.

I claim—

1. In a hydraulic elevator system, the com-
bination of the following instrumentalities,
viz:—an electric circuit containing translat-
ing devices; a continuously running self-regu-
lating motor placed in circuit therewith; a
pressure tank to contain fluid to actuate the
110 elevator; a pump operated by said continu-
ously running motor and delivering into said
pressure tank; and a valve actuated by pres-
sure in the pressure tank to regulate the
amount of delivery from the pump to the
115 pressure tank, substantially as described.

2. In a hydraulic elevator system, the com-
bination of the following instrumentalities,
viz:—an elevator mechanism; a pressure tank
to contain fluid to actuate the same; a dis-
charge tank to receive the discharge from
said elevator mechanism; an electric circuit
containing translating devices; a continu-
ously running self-regulating motor placed
in circuit therewith; a pump operated by said
125 continuously running motor and taking its
supply from said discharge tank and deliv-
ering into said pressure tank, and a valve
actuated by pressure in the pressure tank to
regulate the amount of the delivery from the
130 pump to the pressure tank, substantially as
described.

3. In a hydraulic elevator system, the com-
bination of the following instrumentalities,

viz:—an elevator mechanism; a pressure tank to contain fluid under pressure to actuate the same; a discharge tank to receive the discharge from the said elevator mechanism; an 5 electric circuit containing translating devices; a continuously running self-regulating motor placed in circuit therewith; a pump operated by said continuously running motor, and taking its supply from said discharge 10 tank; a connection between said pump and pressure tank; a branch leading therefrom to said discharge tank, and a valve actuated by the pressure in the pressure tank to open 15 said branch to divert the delivery of the pump from the pressure tank into the discharge tank, substantially as described.

4. In a hydraulic elevator system, the combination of the following instrumentalities, viz:—an electric circuit, a continuously running 20 motor placed therein, a tank to contain fluid to actuate the elevator, a pump operated by said continuously running motor, and

having its delivery pipe connected with said tank, a valve actuated by pressure in the said tank to regulate the amount of delivery from 25 the pump to the pressure tank, and a check valve in said delivery pipe between said valve and tank, to operate, substantially as described.

5. In a hydraulic elevator system, a tank 30 to contain fluid to actuate the elevator, a continuously operated pump delivering into said tank, an electric motor to operate said pump, and a valve actuated by the pressure of the fluid used to actuate the elevator, to control 35 the amount of delivery from the pump to the said tank, substantially as described.

In testimony whereof I have signed my name to this specification in the presence of two subscribing witnesses.

FRANCIS B. PERKINS.
